UNITED STATES PATENT OFFICE.

GUSTAV R. SCHIMMEL, OF DETROIT, MICHIGAN.

HYPODERMIC-SYRINGE-HOLDING ATTACHMENT FOR BOTTLES.

1,116,493.

Specification of Letters Patent.

Patented Nov. 10, 1914.

Application filed October 4, 1912. Serial No. 723,828.

To all whom it may concern:

Be it known that I, GUSTAV R. SCHIMMEL, a citizen of the United States of America, residing at Detroit, in the county of Wayne 5 and State of Michigan, have invented certain new and useful Improvements in Hypodermic-Syringe-Holding Attachments for Bottles, of which the following is a specification, reference being had therein to the 10 accompanying drawings.

In the use of hypodermic instruments and syringes the packing of the plungers and the washers which are necessary in such instruments of this character as are made of 15 metal, frequently dry, so that the instrument does not operate effectively. Where all glass syringes are used the plungers are liable to stick. The needles for such instruments frequently have to be "wired" or 20 otherwise cleaned before use and provision must be made against corrosion or contamination of any sort.

This invention relates to a sterilizer and protector for hypodermic instruments 25 whereby the packing or plunger is kept in workable condition and whereby damage to the needle is guarded against and the latter is kept clean so that it does not need to be "wired" or otherwise attended to before 30 use.

The invention consists in the matters hereinafter set forth particularly pointed out in the appended claims.

In the drawings, Figure 1 is a view in 35 side elevation of a sterilizer and protector that embodies features of the invention; Fig. 2 is a view in front elevation of the instrument; Fig. 3 is a view in elevation showing the modification of the protector 40 for use with instruments that are not provided with finger holds, showing such an instrument supported in the protector and indicating the adjustment of the protector 45 for use with an instrument that has a finger hold; and Fig. 4 is a plan view of the modification.

As herein shown in preferred form a suitable container 1, preferably a salt-mouth bottle, is partially encircled at its neck by a 50 spring clip 2 which may be readily snapped on and off and which is provided with an upright stem 3 that may be formed integrally thereon. A thumb screw 4 in screw-threaded engagement with the stem 3, passes 55 through a longitudinal slot 5 of a rack 6, an outturned lug 7 on the end of the stem 3 co-

operating with the screw to hold the rack in alinement. The latter has a pair of substantially parallel arms 8 that are slightly hollowed to form a secure resting place for 60 the finger pull 9 of a hypodermic syringe or the like. The latter when suspended in the rack passes loosely through the mouth of the container 1 and by proper adjustment of the rack on the stem any syringe 65 may be so supported that the needle point thereof hangs freely in a solution in the container without touching the bottom of the vessel.

For supporting an instrument that does 70 not have a finger pull or equivalent member the rack is modified as shown in Figs. 3 and 4. The forwardly projecting arms 11 which of themselves can support an instrument with a finger pull, are provided with 75 pivot apertures near their outer extremities. A spring member 12 is bent upon itself to form oppositely disposed similar arms having outturned ends 13 that pass through the bearing apertures, the intermediate portion 80 of the arms having concave off-sets 14 substantially in alinement with the throat of the container when the spring member is in operative position, the spring member being proportioned so that its inner end rests 85 on the rack when ready to support an instrument. As indicated in Fig. 5, the spring member readily supports a syringe whose barrel may be snapped into engagement with it. As also indicated in Fig. 5 90 by the dotted lines the spring member may be dropped to allow the insertion of an instrument with finger pull.

When in use the rack is so adjusted to the length of the syringe to which the apparatus is adapted that the needle of the instrument clears the bottom of the bottle. The syringe may be filled by drawing up the plunger to its limit.

A device of this character keeps an instrument in usable and aseptic condition 100 with the packing and plunger moistened so that the instrument does not leak and can be instantly brought into use.

Obviously, changes in the details of construction may be made without departing 105 from the spirit of the invention and I do not care to limit myself to any particular form or arrangement of parts.

What I claim is:—

1. A rack of the type described comprising a vertical stem adapted to have the lower

- end thereof detachably connected to the neck of a receptacle, a vertical rack adjustably supported by said stem, rigid arms carried by the side edges of said rack and projecting from one side thereof and adapted to extend over the mouth of the receptacle, and means arranged between said arms adapted to support an article in a suspended position relative to said arms.
- 10 2. A rack of the type described comprising a vertical stem, resilient clips carried by the lower end thereof, a set screw carried by said stem, a vertical rack adjustably held against said stem by said set screw, rigid arms carried by the upper end of said rack, and means arranged between said arms and adapted to support an article in a suspended position relatively thereto.
- 20 3. A rack of the type described comprising a vertical stem, resilient clips carried thereby and adapted to engage a receptacle, a lug carried by the upper end of said stem, a vertical rack having a slot formed therein to receive the lug of said stem, a set screw carried by said stem and adjustably holding said rack against said stem, parallel arms carried by said rack, and means carried by said arms adapted to hold an article in a suspended position.
- 25 4. A rack of the type described comprising spring clips adapted to yieldably embrace the neck of a receptacle, an upright stem carried thereby and provided with an
- out-turned lug, a rack longitudinally slotted to engage the lug of said stem, a set screw 35 on the stem engaging the rack for clamping the same against said stem, a pair of arms on the rack adapted to support an article, and a spring member pivotally secured to the arms of the rack and adapted when 40 turned into substantially horizontal position on the rack to support an article.
5. A rack of the type described comprising spring clips adapted to yieldably embrace the upper portion of a receptacle, an 45 upright stem carried thereby and provided with a lateral projection, a rack having a depending longitudinally slotted portion in sliding engagement with the stem and the projection thereof, a pair of substantially 50 parallel arms forming part of said rack, a clamping member for holding said rack relatively to said stem, and a spring member bent upon itself to form oppositely disposed similar arms with out-turned end 55 portions pivoted in bearing apertures in the arms of said rack, the spring member being adapted to rest in the rack when turned in substantially horizontal position.

In testimony whereof I affix my signature 60
in presence of two witnesses.

GUSTAV R. SCHIMMEL.
